United States Patent Office

Des. 184,390
Patented Feb. 10, 1959

184,390

COMBINED STEP AND STOOL

Harold W. Cramer, Hickman Mills, Mo.

Application October 14, 1958, Serial No. 52,973

Term of patent 14 years

(Cl. D15—8)

Fig. 1 is a perspective view of a combined step and stool, showing my new design, and

Fig. 2 is a top plan view thereof.

I claim:

The ornamental design for a combined step and stool, as shown.
